(57) **CLAIM**

We claim the ornamental design for a dual purpose flip-out and T handle wrench, as shown and described.

DESCRIPTION

FIG. 1 is a front view of the handle;

FIG. 2 is a back view of the handle;

FIG. 3 is a left side view of the handle;

FIG. 4 is a right side view of the handle;

FIG. 5 is a bottom view of the handle;

FIG. 6 is a top view of the handle;

FIG. 7 is a perspective view of the handle in a flip-out configuration; and,

FIG. 8 is a perspective view of the handle in a T configuration.
